TRANSISTORIZED IGNITION SYSTEM

Gerald M. Ford, Kokomo, Ind., assignor to General Motors Corporation, Detroit, Mich., a corporation of Delaware

Filed Mar. 6, 1958, Ser. No. 719,661

2 Claims. (Cl. 315—92)

This invention relates to an improved ignition system for internal combustion engines. With the conventional ignition coil-breaker type of ignition system currently in use, there is a definite maximum voltage obtainable from the secondary winding with a storage battery source connected in the primary. It is desirable to provide a high secondary voltage to apply to the spark plugs in order to obtain satisfactory ignition of the combustible mixture in the cylinder and also to reduce wear on the electrodes of the spark plugs. In the past, it has been found that a turn ratio of 100-1 in the ignition transformer is the optimum. At any higher turn ratio, the distributed capacity of the coil is a limiting factor and nothing is gained from a practical standpoint. This has limited the voltages used with conventional coils and breaker systems to some 17,000 volts. It would be advantageous to the ignition system to be able to obtain thirty thousand volts or perhaps more.

It is an object in making this invention to provide an ignition system producing higher secondary voltages and greater energy transfer than have heretofore been obtainable.

It is a further object in making this invention to provide an ignition system in which uniformly high secondary voltages are available over the full range of engine speed.

It is a still further object in making this invention to provide an ignition system for an internal combustion engine utilizing transistors for controlling current flow.

With these and other objects in view which will become apparent as the specification proceeds, the invention will be best understood by reference to the following specification and claims and the illustration in the accompanying drawing in which:

The figure is a circuit diagram showing an ignition system embodying my invention.

Referring now more specifically to the drawing, there is shown therein a conventional automobile battery 2, one terminal of which is grounded and the other terminal connected to a movable switch arm 4 which moves between two stationary contacts 6 and 8. A second movable switch arm 10 is electrically connected to switch contact 8. The second arm 10 oscillates between two fixed contacts 12 and 14. These switches control the ignition system to operate either conventionally or to include the transistor control. The ignition system includes a breaker 16 for intermittently interrupting the primary current in either the primary winding 18 of the control transformer 20 or primary 58 of the ignition transformer 60. The breaker includes a movable switch arm 22 which is connected to ground through line 24. The arm 22 pivots around pin 26 and is engageable with a stationary contact 28 insulatedly mounted on plate 30 depending upon the angular position of a rotatable cam 32. The raised points of the cam 32 force the pivoted arm 22 outwardly to open the circuit and at low points allow the switch contacts to close. Cam 32 is of course driven by the cam-shaft of the engine. Contact 28 is connected through line 34 with a movable switch arm 36 of a control relay

38. Control relay 38 is provided to switch from conventional ignition circuit operation to the transistorized system and has an operating coil 41 for attracting the armatures toward their lowermost position. This coil 5 has one terminal connected to ground and the other terminal through line 43 to stationary contact 14 on the on-off switch.

Switch arm 36 oscillates between two fixed contacts 40 and 42 and is spring biased towards its upper position 10 by spring 44. Movable switch arm 36 is ganged mechanically to move with two other arms 46 and 48 as shown by the dash line connection between the three arms. The movable switch arm 46 is connected through conductor 50 with contact 8 of the on-off switch. This switch arm 15 oscillates between two fixed contacts 52 and 54. The last switch arm 48 is connected through conductor 56 to primary 58 of the ignition transformer 60. Switch arm 48 oscillates between two fixed contacts 62 and 64. Contact 64 is connected directly to ground and contact 62 is connected through conductor 66 to stationary contact 52. Contact 54 is connected through conductor 68 with one terminal of the primary winding 18 of control transformer 20. The opposite terminal of the winding 18 is connected through conductor 70 with fixed contact 42 25 of relay 38. Stationary contact 40 is connected through line 72 to the remaining terminal of the primary winding 58 of the ignition transformer 60. The control transformer 20 is provided with a plurality of secondary windings whose function it is to provide base-emitter bias 30 for a plurality of transistors or three element semiconductor devices all of which are connectable in series between a source of power and the primary 58 of the ignition transformer.

Transistors 74, 76, 78, 80, and 82 have their adjacent 35 collectors and emitters connected together so that they are all, in effect, connected in series. Secondary windings 84, 86, 88, 90, and 92 are connected respectively across the base-emitter electrodes of each of the transistors 74, 76, 78, 80, and 82 respectively. A tieline 94 extends 40 between contact 54 and the emitter electrode 96 of transistor 74. Collector 98 of transistor 82 at the other end of the chain is directly connected to line 72 and thence to the primary winding 58. The high tension secondary winding 100 of the ignition transformer coil 60 has one 45 terminal connected to ground and the other connectable to any spark plug such as 102 which is merely shown to diagrammatically illustrate any spark plug or series of spark plugs.

The two main objects of the current system are to 50 provide as high primary current as can be obtained in order to obtain maximum energy, and also to obtain a sharp cut-off. Such a system would minimize wear on the distributor points and also minimize the effect of spark plug electrode misalignment or spark plug fouling. 55 An added result is that this system tends to give a very uniform output over the complete driving speed range.

In describing the operation, the driver moves the switch 4—10 to the On position. This connects the battery to the system for operation as a transistorized control circuit. The initial result is the completion of an energizing circuit for the coil 41 of the control relay 38. This coil is energized through the following circuit: from battery 2, switch arm 4, contact 8, line 45, switch arm 10, contact 14, line 43, coil 41 to ground. The energization of this 65 coil causes it to attract the three ganged armatures 36, 46 and 48. This completes an energizing circuit for the primary coil 18 of the control transformer 20 as follows: battery 2, switch arm 4, contact 8, line 59, armature 46, contact 54, line 68, primary winding 18, line 70, contact 42, armature 36, line 34, contact 28, arm 22, line 24, to ground. Thus, when the contacts of the distributor close, an energizing pulse is caused to flow through the wind-

ing 18. This induces currents in the various secondary windings 84, 86, 88, 90, and 92 to produce a proper emitter-base bias in each of the transistors to permit a heavy current flow from the power source through the transistors to the primary 58 and a resultant high voltage to be induced in the secondary 100. The circuit for the primary 58 of the ignition transformer is from the battery 2, switch arm 4, contact 8, line 50, armature 46, line 68, line 94, through the various transistors 74, 76, 78, 80, and 82 in series to line 72 and then through the primary winding 58, line 56, armature 48, contact 64 to ground. This last circuit, of course, is not broken during the operation of the system.

The triggering or firing pulses are produced by changing the bias on the transistors due to the opening and closing of the primary circuit 18 of the control transformer 20. When a pulse is induced, the transistors are biased to conduct in a forward direction, causing heavy current to flow through the primary 58 and induce a high charging voltage in the secondary 100. At this time the resistance of the transistors is low so that a maximum current can flow and a maximum amount of energy be obtained. When the points open, the bias is changed to effectively cut off the current. However, upon a collapse of the field in the ignition transformer, a high voltage will be induced in the primary winding 58. It is then desired to have the transistors appear as high resistance for current which they provide and very little current flows. By applying maximum energy and high voltage to the spark plugs, the effects of burning or erosion will be minimized and by interrupting only the current in the low voltage primary of the control transformer 20, the wear on the breaker points will also be minimized.

If desired, the ignition circuit can be operated in a conventional manner by moving switch arm 10 from engagement with contact 14. This deenergizes relay coil 41 and it therefore allows all of its armatures 36, 46 and 48 to be pulled upwardly. Through an obvious circuit, the battery is now directly connected only through the primary winding 58 of the ignition transformer 40 and the contact points 22 and 28 so that the ignition system may now be operated conventionally without the transistors being introduced into the circuit.

I claim:

1. In an ignition system for an internal combustion engine having spark plugs for igniting the combustible mixture and distributor points for breaking a circuit synchronized with engine operation comprising a source of

electrical power, an ignition transformer having a low tension and a high tension winding, said high tension winding being connectible to said spark plugs, a plurality of transistors having base, collector and emitter electrodes connected in series relation so that the emitter electrode of one is connected to the collector electrode of the adjacent transistor and current flows through the transistors in series, said series group being connected to said source of electrical power and to the low tension winding so that the transistors each and in combination, control the current flow through the low tension winding, a control transformer having a primary and a plurality of secondary windings inductively coupled to said primary winding, each secondary winding being connected across the base and emitter electrodes of one of the transistors, and the primary winding being connected in circuit with the source of electrical power and distributor points to apply a pulsating voltage thereto and control the flow of current through the transistors for ignition purposes.

2. In an ignition system for an internal combustion engine having spark plugs for igniting the combustible mixture and distributor points for breaking a circuit synchronized with engine operation comprising a source of electrical power, an ignition transformer having a low tension and a high tension winding, said high tension winding being connectible to said spark plugs, a three terminal semiconductor device having an input and an output circuit, said output circuit being connected to said low tension winding, biasing means connected to said semiconductor device and providing a controlling bias to vary the current flow through the semiconductor device, switching means interconnecting said low tension winding, the semiconductor means, the source of electrical power and the distributor points or alternatively the low tension winding, the source of electrical power and the distributor points so that the ignition system may be operated either with or without the semiconductor device and means for actuating said switching means.
